[57] CLAIM

The ornamental design for a film spool, as shown and
described.

[21] Appl. No.: 865,306

DESCRIPTION

[22] Filed: Dec. 28, 1977

FIG. 1 is a perspective view of a film spool showing my
new design;
FIG. 2 is a front elevational view thereof;
FIG. 3 is a side elevational view thereof, the opposite
side being a mirror image of the side shown;
FIG. 4 is a rear elevational view thereof;
FIG. 5 is a top view thereof; and
FIG. 6 is a bottom view thereof.
